His Attorney

UNITED STATES PATENT OFFICE.

AUGUST MEYER, OF WELLSTON, MISSOURI, ASSIGNOR TO HANDLAN-BUCK MANUFACTURING COMPANY, OF ST. LOUIS, MISSOURI, A CORPORATION OF MISSOURI.

SIGNAL-LAMP.

1,351,113.

Specification of Letters Patent. Patented Aug. 31, 1920.

Application filed July 2, 1919. Serial No. 308,210.

To all whom it may concern:

Be it known that I, AUGUST MEYER, a citizen of the United States of America, a resident of Wellston, in the county of St. Louis, State of Missouri, have invented certain new and useful Improvements in Signal-Lamps, of which the following is a full, clear, and exact description, reference being had to the accompanying drawings, forming a part of this specification.

My invention relates to signal lamps for railway use, and has for its object to provide within a lamp of this kind a rotatable screen movable relative to a lens or lenses of the lamp, and which may include either a shield for preventing the passage of rays of light from the interior of the lamp through a lens, or colored plates through which the rays of light pass to be projected through the lens. Lamps having rotatable screens of the kind mentioned have been heretofore made, but they are unsuited for the employment of electric lamps, which should be stationarily mounted with provision for the rotation of the screen relative to the electric lamp. By my improvement, I mount an electric lamp socket in a stationary position upon the base of a signal lamp shell and provide for the rotation of the screen around the electric lamp socket, so that the movement of the screen may take place without movement of the electric lamp.

Figure I is a top plan view of my signal lamp with the lid open.

Fig. II is a vertical section taken on irregular line II-II, Fig. I.

Fig. III is an inverted plan of the lamp.

In the drawings, A designates the shell of my signal lamp which includes a base plate 1, and has fitted thereto any suitable number of lenses 2.

Within the lamp shell is an electric lamp socket 3 which receives a lamp bulb 3', and to which electric current is delivered through conducting wires 4 leading through the shell of the lamp. The lamp socket 3 is supported by the base plate 1 of the signal lamp shell to which it is secured in a central position, so that it remains stationary during the use of the signal lamp. Around the lamp socket 3 is an annular rim 5 projecting upwardly from the base plate 1, said rim being preferably produced from a plate 6 mounted on

the base plate, and constituting a seat for the electric lamp socket.

7 designates a carrier ring loosely seated on the base plate 1 concentric with the rim 5 surrounding the electric lamp socket, and having at its inner margin an upturned annular flange 8 movable in contact with the rim 5, which serves as a guide during rotative movement of the carrier ring 7. At the outer margin of the carrier ring 7 is an upturned flange 9, which contacts loosely with the shell of the lamp, said shell being preferably provided with an inwardly extending rounded annular bead 10 located opposite to the marginal flange 9, which by contact with the vertical flange of the carrier ring reduces the degree of frictional contact between said flange and the lamp shell.

The carrier ring 7 supports a screen 11, movable to and from the lenses of the signal lamp upon rotation of the carrier ring.

To provide for the operation of the carrier ring 9 without opening the signal lamp, I form an opening 12, preferably a curved slot, in the base plate 1 of the signal lamp shell, and extend through said opening an operating member 13, which may be in the form of a handle such as shown in Figs. II and III, or of any other suitable form.

I claim:

1. In a signal lamp, a shell, a lamp centrally disposed in said shell above the bottom thereof, a rim surrounding said centrally disposed lamp, and a screen carrier comprising a ring interposed between said rim and the signal lamp shell, said shell having a rounded annular bead and said carrier ring having a marginal flange contacting with each other.

2. In a signal lamp, a shell, a lamp centrally disposed in said shell and spaced above the bottom thereof, a rim surrounding said centrally disposed lamp, and a screen carrier comprising a ring rotatable upon the outer periphery of said rim, said ring being provided with an inner marginal flange contacting with the rim surrounding the centrally disposed lamp, and also provided with an outer flange contacting with the inner wall of said shell.

In testimony that I claim the foregoing I hereunto affix my signature.

AUGUST MEYER.
